UNITED STATES PATENT OFFICE.

WILLIAM V. D. KELLEY, OF NEWARK, NEW JERSEY, ASSIGNOR OF ONE-HALF TO HOWARD S. JONES, OF BROOKLYN, NEW YORK.

EXHIBITING DEVICE.

No. 876,907.

Specification of Letters Patent.

Patented Jan. 14, 1908.

Application filed April 30, 1906. Serial No. 314,392.

To all whom it may concern:

Be it known that I, WILLIAM V. D. KELLEY, a citizen of the United States, residing at Newark, in the county of Essex, State of New Jersey, have invented certain new and useful Improvements in Exhibiting Devices, of which the following is a specification.

This invention relates to exhibiting devices and has particular reference to a transparency which varies in appearance according as it is viewed by reflected or transmitted light.

The object of the invention is to provide a transparency or sign adapted to be used for exhibition purposes, having a complete picture on each side, with an intervening translucent medium, the pictures being so arranged that when the transparency is illuminated by transmitted light, the picture on the back is distinguishable, and the picture on the front indistinguishable, and when illuminated by reflected light, only the picture on the front is visible, as in an ordinary sign or card. This object I may carry out in various specific ways, according to the nature and character of the pictures or signs, as photographs, half-tones, etc., but in general, my invention consists in forming the respective pictures in contrasting sections and in disposing the sections so that when viewed by transmitted light, the front picture will be obscured and the rear picture rendered visible without interference, but when seen by reflected light, the front picture only will be visible, the rear one being obscured by the intervening medium. In the preferred form of my invention, I form such a duplex sign or picture exhibiting device by printing or otherwise forming on one side of the translucent medium a series of parallel lines separated by spaces of equal width, and then print the rear picture over these lines. The front picture also consists of lines and spaces, with the lines overlying those of the rear picture so as to be obscured thereby when that portion of the rear picture between the lines becomes visible by transmitted light. In this manner, which can be carried out by various different arrangements, the front picture, which is visible in reflected light by reason of its own contrast with the surface, becomes entirely obscured or blotted out by the lines on the

other side, in transmitted light, leaving the rear picture visible in contrast with the darker background produced by the lines. In practice, the width of the lines and spaces will be determined according to the use to which the device is to be put. For instance, in post cards, lines and spaces as fine as one hundred to the inch might be used, and in large signs with the observer some distance away, considerably coarser lines could be employed without injuring the effect.

The accompanying drawing illustrates one manner of carrying out my invention, wherein,

Figure 1 shows the rear picture, Fig. 2 the front picture, and Fig. 3 a section of a display apparatus embodying my invention.

In Fig. 1 is shown the rear picture having the equidistant contrasting portions, as lines and spaces over which the picture to be exhibited by transmitted light is printed, being as shown the letter "P". The front picture is composed of alternate lines and spaces, sufficiently close together to produce the impression of a substantially continuous picture, and is so placed that the lines and spaces coincide respectively with those of the rear picture, so that when the rear picture is to be viewed, the parts thereof between the lines on the back appear in the spaces of the front picture, while the whole of the front picture is blotted out by the lines on the back. In this manner two entirely distinct pictures separated by a translucent medium can be successively exhibited, without involving any interference of one with the other.

In Fig. 3, 1 represents a box, 2 the transparency, 3 lights for exhibiting the front picture 4 by reflected light, 5 the translucent medium, 6 the rear picture, 7 lights for exhibiting the rear picture by transmitted light, and 9 an electric switch for operating the lights.

The invention can be carried out in various ways, according to the character of the pictures, and the rear picture may be opaque and appear as a shadow, or it may be colored and appear as does an ordinary colored transparency. The front picture can also be of various kinds, and the translucent separating medium 5, whose function is to exclude the rear picture except when lighted from behind, may be of paper, stippled paint, or

other material such that it will transmit light without permitting reflection of the rear picture.

I have devised a method of photographically producing a transparency which consists in printing the lines for the rear picture on one side of a sheet of translucent material, sensitizing both sides, then printing the rear picture from an ordinary negative on the rear side, and printing the front picture on the other side from a negative with an interposed screen having lines corresponding to those on the rear side, but displaced therefrom so as to cover the spaces, and thereby enabling the rear lines to blot out the front picture in the manner as before described. This forms a cheap and rapid way of carrying out my invention, but it will be seen that half-tone pictures, colored prints and all kinds of reproductions may be exhibited in this manner, and thereby a novel and simple device produced for advertising or exhibition purposes. Various arrangements of colors will produce very novel effects, when exhibited in this manner. It will also be seen that the pictures may be on glass with the intervening translucent medium formed by stippling one side, or it may be cloth or paper or ground glass, without in any way departing from the invention. Also, the obscuring lines for the front picture could be printed or ruled on the intervening medium without varying from the scope of the invention and the lines need not be continuous as long as certain parts are obscured and others rendered visible. In general, it may be said that the thinner the whole transparency is, the better will be the effects produced, provided reflection from the rear picture be prevented by a satisfactory medium. Furthermore, the rear side need have only lines and spaces, in case it is desired to provide a display device in which the front picture will be invisible in transmitted light.

Having thus described my invention, I declare that what I claim as new and desire to secure by Letters Patent, is,—

1. An exhibiting device comprising a translucent medium having a plurality of sectional pictures, the respective sections being alternately arranged, and a screen having opaque sections coinciding with the sections of one picture to render it invisible in transmitted light, said latter picture being only visible in reflected light, substantially as described.

2. An exhibiting device comprising a picture made of alternately arranged contrasting sections on a translucent medium, said picture being visible in reflected light, and an opaque screen behind said picture having sections coinciding with the sections of said picture whereby to render said picture invisible in transmitted light, substantially as described.

3. An exhibiting device comprising a picture made of alternately arranged contrasting sections on a translucent medium, said picture being visible in reflected light, and an opaque screen behind said picture having sections coinciding with the sections of said picture whereby to render said picture invisible in transmitted light, and a second picture rendered visible in transmitted light between the opaque sections of said screen, substantially as described. 65
70
75

4. In an exhibiting device, the combination of a plurality of superposed pictures and an intervening translucent medium, one of the pictures having a background contrasting therewith in part to render said picture visible by transmitted light, and harmonizing in part with the other picture to render said other picture at the same time invisible in transmitted light, substantially as described. 80
85

5. In an exhibiting device, the combination of a plurality of superposed pictures and an intervening translucent medium, one of the pictures having a background contrasting therewith in part to render said picture visible by transmitted light, and harmonizing in part with the other picture to render said other picture at the same time invisible in transmitted light, the latter being only visible in reflected light, substantially as de- 90
95
95cribed.

6. An exhibiting device comprising a translucent body with lines and spaces on the rear side, and on the front side a picture composed of lines and spaces coinciding therewith, whereby the picture is invisible in transmitted light, substantially as described. 100

7. An exhibiting device comprising a translucent body with lines, spaces and a picture on the rear side thereof, and on the front side a picture composed of lines and spaces coinciding with the lines and spaces on the rear side, substantially as described. 105

8. An exhibiting device comprising a translucent body with lines and spaces of equal width on the rear side, and on the front side a picture composed of lines and spaces coinciding therewith, whereby the picture is invisible in transmitted light, substantially as de- 110
115

9. The combination with a transparency comprising a translucent body with lines and spaces on one side, and on the other side a picture composed of lines and spaces coinciding therewith, of lighting devices on each side 115
120
125 of said transparency, the lights on one side rendering the picture visible, and on the other side invisible, substantially as described.

10. The combination with a transparency comprising a translucent body with lines, spaces, and a picture on one side, and on the other side a picture of lines and spaces coin-

ciding with the lines and spaces on said first mentioned side, of lighting devices on each side of said transparency and alternately operable to render one or the other of said pictures visible, substantially as described.

5 In testimony whereof, I have signed my name to this specification in the presence of

two subscribing witnesses, this 27th day of April 1906.

WILLIAM V. D. KELLEY.
